US0D1044075S

(12) **United States Design Patent** (10) Patent No.: **US D1,044,075 S**
(45) Date of Patent: ** Sep. 24, 2024

(54) **MULTIFUNCTIONAL LED BOOK CLIP LIGHT**

(71) Applicant: **Shenzhen Chuangchaoxin Digital Technology Co., Ltd.**, Shenzhen (CN)

(72) Inventor: **Lan Tao**, Shenzhen (CN)

(73) Assignee: **Shenzhen Chuangchaoxin Digital Technology Co., Ltd.**, Shenzhen (CN)

(**) Term: **15 Years**

(21) Appl. No.: **29/792,819**

(22) Filed: **Apr. 26, 2022**

(51) LOC (14) Cl. **26-05**

(52) U.S. Cl.

USPC **D26/63**

(57) **CLAIM**

The ornamental design for a multifunctional LED book clip light, as shown and described.

DESCRIPTION

FIG. 1 is a front elevation view of a multifunctional LED book clip light showing the new design;
FIG. 2 is a back elevation view thereof;
FIG. 3 is a left-side view thereof;
FIG. 4 is a right-side view thereof;
FIG. 5 is a top plan view thereof;
FIG. 6 is a bottom plan view thereof;
FIG. 7 is a top-left perspective view thereof;
FIG. 8 is a perspective view thereof.

FIG. 9 is a perspective view of the unfolding status thereof; and,

FIG. 10 is a perspective of the unfolding status thereof view thereof.

The broken lines show portions of the article that form no part of the claimed design.

1 Claim, 10 Drawing Sheets
